FIG. 6.

UNITED STATES PATENT OFFICE.

FRANZ X. WAGNER, OF NEW YORK, N. Y.

TYPE-WRITING MACHINE.

SPECIFICATION forming part of Letters Patent No. 364,556, dated June 7, 1887.

Application filed January 28, 1886. Renewed February 9, 1887. Serial No. 227,092. (No model.)

To all whom it may concern:

Be it known that I, FRANZ X. WAGNER, a citizen of the United States, residing at New York, in the county and State of New York, 5 have invented new and useful Improvements in Type-Writing Machines, of which the following is a specification.

My invention relates to improvements in type-writing machines; and it consists in the 10 combination of certain parts, all of which are more fully pointed out in the following specification and claims, and illustrated in the accompanying drawings, in which—

Figure 1 represents a horizontal section in the plane $x-x$, Fig. 2, of a type-writer constructed according to my invention. Fig. 2 is a vertical transverse section of the same in the plane $y-y$, Fig. 1. Fig. 3 is a front elevation thereof, showing the mechanism for adjusting the type-carrier so as to bring either of the rows of type into the printing-line, and of the adjacent parts. Fig. 4 is a plan view of the device for rotating the type-carrier so as to bring an individual type into the printing-line. Fig. 5 is a rear elevation of the carriage-feeding mechanism. Fig. 6 is a sectional elevation of the mechanism for imparting to the platen a motion toward and from the type-carrier.

Similar letters indicate corresponding parts. In the drawings, the letter A designates the base-plate of the type-writer; B, the type-carrier, which is shown in the form of a wheel and has arranged upon its periphery one or 35 more horizontal rows of type.

C is the platen, Figs. 2 and 6, which has journal-bearings in the side levers, D D, of the platen-carriage. The said platen-carriage can swing about a bar, d, to which it is hinged at d' d'. A pressure-roller, d², having slot-bearings and clamps d³, together with the usual ratchet-wheel and pawl, (not shown in the drawings,) are provided as means for holding and feeding the paper, and may be of any 45 well-known construction. Across the side levers, D D, and secured to the arms d' thereof, is a tie-rod, d⁵, which is engaged by a lever, D', which is secured to a frame, D², that can turn on a shaft, D³, having bearings in lugs a' of 50 the base-plate. It is obvious that when this lever D' is depressed the platen-carriage is

caused to turn about the bar d as a fulcrum, and the platen C is moved toward and brought in contact with one of the type on the type-carrier B, and when the said lever D' is released the platen-carriage will fall back from its own weight. To return the lever D' to its normal position it is subjected to the action of a spiral spring, D⁴.

The type-carrier B is mounted to rotate 60 about a hollow shaft, E, and can also be adjusted vertically thereon, the first movement being essential to bring each type into the printing-line and the second movement to bring each row to the level of the printing-line.

To rotate the type-carrier, and at the same time to provide means for depressing the platen-lever D', so as to vibrate the platen, I employ a key, F, having a shank, f, which extends downwardly through the hollow shaft E and impinges upon the said platen-lever, and is supported thereby. From the shank f of the key extends a horizontal arm, which is provided with a pin, f', that engages with a 75 slot, f², in an arm or web, f³, of the type-carrier B, so that by rotating the key F the type-carrier B is rotated, and by depressing the said key the platen C is brought against the type-carrier through the medium of the lever D'. To facilitate the manipulation of the key, the shank f is provided with a knob and plate, which are attached to its upper end.

Pendent from a hinged lid or cover, K, is a guide-plate, G, containing a series of notches 85 or guides, g, on its periphery, and upon the upper surface of the lid or cover is arranged an index-plate, H, which bears the letters, arranged in alphabetical order, and also the numerals, punctuation-marks, and other signs 90 which may be found in the type on the type-carrier. From the key F extends a pointer or index-hand, I, Figs. 4 and 6, in the same plane with the index-plate.

The notches or guides g in the guide-plate 95 G taper downward, and the key F is provided with a tooth, f⁴, which engages one of the notches or guides in the guide-plate when the key is depressed. It will be observed that the pin f' on the key F travels in a path which 100 lies beyond the periphery of the guide-plate G, but that the tooth f⁴ thereon travels di-

rectly above the guides g , and therefore, when the key is depressed after rotating the same to the desired letter, as pointed out on the index-plate, this tooth will enter one of the corresponding guides, and the desired letter is guided to and held firmly in the printing-line.

J J, Figs. 1, 2, and 3, are the inking-rolls, which are mounted so as to be capable of rotation upon vertical arbors $j j$, Fig. 1, which are secured in the arms $j' j'$ of supports J' , swiveled upon a bracket, J' , that is provided with a sleeve, and said sleeve is fitted to the hollow shaft F. The bracket J^2 can be shifted vertically upon said shaft and is guided by a post, j^2 , secured in the base of the shaft E. To hold the inking-rolls in contact with the types on the type-carrier, a flat spring, J^3 , is secured to the brackets at its center, and the ends of this spring are in contact with arms $j^3 j^3$ of the supports J' .

When the rows of type are arranged upon the type-carrier, as in the example shown in the drawings, the center row, which, for convenience, contains the small letters of the alphabet, is arranged in the level of the printing-line, and one of its types produces an impression when the type-wheel is in its normal position, as shown in full lines in Figs. 2, 3, and 6. To obtain an impression from the remaining two rows of type on the paper carried by the platen, it is necessary that the type-carrier B, together with the ink-rolls J J, should be respectively raised or lowered through the proper distance to bring the respective row of type in the position previously held by the center row of type. For this purpose the bracket J^2 , upon which the type-carrier also rests, is carried upon an inclined cam, L, secured to or formed integral with an arm, l, Figs. 1, 2, and 3, which extends from a frame, L' , that can rotate about an arbor, L^2 , so that when the said cam is swung radially about its points of pivoting the ink-rolls and type wheel are elevated, or vice versa.

The arbor L^2 is supported at its bottom in the base-plate, while its top is restrained in a bracket, M, which is supported upon two standards, $m m'$. A spring, L^3 , which is coiled about the arbor L^2 , tends to hold the frame in a definite position. To this bracket M is also hinged the cover K, previously referred to.

From the frame L' extends a movable finger-piece, N, which is arranged centrally between two stationary thumb-pieces, $N' N^2$, which project from the standards m and m' , respectively, and serve as a stay for the hand in moving the finger-piece. When the finger-piece N is in its normal position, the center row of type is in the printing-line. When the same is drawn against the thumb-piece N' , the bottom row of type is in the printing-line, and when the finger-piece is against the thumb-piece N^2 the top row of type is in the printing-line, the type-carrier being always returned to its normal position by the action of the spring L^3 .

In order to obtain the necessary space between the consecutive letters, a rack, O, is se-

cured to the back of the base-plate, which is engaged by a gravitating spacing-dog, O', that is carried by an arm, o, which extends from the frame of the platen-carriage; Figs. 1, 2, 5, and 6. The spacing-dog O' is provided with teeth $o' o^2$, one at each end, and is pivoted to the arm o at the point between the teeth $o' o^2$, but nearer the tooth o^2 , so that when the spacing-dog is free to move, it turns about the arm o and the portion carrying the tooth o' moves toward the rack. When the platen is moved in its vibratory motion toward the type-carrier by the depression of the key F, the spacing-dog is immediately raised and the teeth $o' o^2$ are cleared from the rack; but during such elevation the said dog turns about the arm o, as above stated, and consequently the tooth o' is brought into the position shown by dotted lines in Fig. 5, or one tooth in advance. When the platen falls back from the type-carrier on release of the key F, the dog is carried with the same and now turns about tooth o^2 as a fulcrum to the position shown in full lines in Fig. 5, and consequently the carriage has been advanced a distance equal to the pitch of the teeth on the rack.

To obtain the space between two consecutive words, a spring-pressed stop-rod, R, is arranged in bearings r in the base-plate A, having at one end a button, while its other end is in a proper position to extend under the lever D' when the latter is in its raised position, as shown by full lines in Fig. 2. If the stop-rod R is pushed inward, so as to extend under the lever D', and the key F is depressed, the lever D' comes into contact with the stop-rod, which arrests its motion, so that the platen g, although moved sufficiently to actuate the spacing device, does not come into contact with the type on the type-carrier. The paper-carriage, however, moves sufficiently to advance the carriage by one tooth, whereby the desired space is obtained.

To return the carriage after it has arrived at the end of its travel, a clearing-lever, S, Figs. 1 and 2, which is secured to the rock-shaft D', actuates a flat bar, S', which bar is in position to engage with a pin, s, upon the spacing-dog O, thereby lifting the same out of engagement with the rack. The type-carrier, instead of being in the form of a wheel, may be a segment. To replenish the inking-rolls J J, which are covered with any material which soaks up the ink, it is necessary to remove the same, which is done by opening the hinged cover or lid and then removing the key F and the type-carrier B, when the rolls can be lifted out, together with their lever-supports, or the entire roll-bracket may be removed. To prevent the inopportune falling out or removal of the key, a small lateral projection, h, is formed on the pin f', which extends inwardly beyond the base of the teeth, Fig. 2, and to remove the key it is necessary to move the same to a recess, h', Fig. 4, in the guide-plate G. A latch, T, pivoted to the lid or cover, is provided to close access to the recess and to limit the sweep of

the key, and consequently the rotation of the type-carrier.

To render the adjustability of the type-carrier B in a horizontal plane more accurate, 5 the thumb-pieces N' N² are each provided with adjusting-screws n' n², against which the finger-piece N impinges.

What I claim as new, and desire to secure by Letters Patent, is—

10 1. The combination, with the type-carrier and vibrating platen-carriage, of the lever D, engaging said carriage, the guides for the type-carrier, a key having an arm engaging said guides and the type-carrier, and a shank which 15 engages the carriage-operating lever, and the stop-rod R, constructed to engage with the lever for word-spacing, substantially as shown and described.

20 2. The combination, with a type-carrier carrying two or more rows of type arranged upon its face, of a platen, inking-rolls in contact with the type, a bracket supporting the type-carrier and the inking-rolls, and the spring-pressed cam, and the finger-piece and thumb-piece for adjusting the position of the type-carrier to bring either row of type to the level of 25 the printing line, substantially as shown and described.

30 3. The combination, with a rotary type-carrier, of a number of (two or more) rows of type upon its face, a platen-carriage, inking-rolls in contact with the type, guides for the type-carrier, constructed to allow each type to be moved into the printing-line, a key provided with a shank which is connected with 35 the platen-carriage, a pin on said key engaging the guides for the type-carrier, also an inclined cam carrying the type-wheel and inking-rolls, and means, such as shown and described, 40 for operating said cam.

45 4. The combination, with the rotary type-carrier B, of the bracket J², the inking rolls J J², in contact with the type-carrier, the lever-supports J' J', attached to the bracket J² and 50 carrying the inking-rolls, and the spring J³, engaging the lever-supports, substantially as shown and described.

55 5. The combination, with the type-carrier B, bearing a number of (two or more) rows of type upon its face, of the spring-pressed cam constructed to swing radially and support the

type-carrier B, substantially as shown and described.

6. The combination, with the carrier B, containing a number of (two or more) rows of type 55 upon its face, of the spring-pressed frame L', suitably pivoted, the cam L, connected with said frame, the finger-piece N, and thumb-pieces, substantially as shown and described.

7. The combination, with the base-plate A, 60 of the rack O thereon, the platen-carriage, the spacing-dog O', hinged to the carriage, and the teeth o' o² thereof, constructed to engage said rack, substantially as shown and described. 65

8. The combination, with the base-plate A, of the rack O thereon, the platen-carriage, the spacing-dog hinged to the carriage, the bar S', and lever S, for lifting the spacing-dog from the rack, substantially as shown and described. 70

9. The combination, with the rotary type-carrier containing a number (two or more) of rows of type upon its face, and a platen movable to and from the type-carrier, of the guides g, to move each type on the carrier in the printing-line, a lever, D', engaging the platen-carriage and in contact with the end of key F, the inking-rollers J J², in contact with the type, the bracket U², supporting said inking-rolls and also the type-carrier, and the cam L, supporting the bracket, which cam is constructed to raise or lower the type carrier to bring either of the rows of type to the printing-line, substantially as described. 75

10. The combination, with the type-carrier 80 B and the platen-carriage, of the lever D', engaging the same, the plate G, provided with notches or guides g, the key F, having a shank, f, which impinges upon the lever D', an arm extending from said shank, a pin, f', which 90 swings outside of the guides and engages the type-carrier to rotate the same with the key, and a tooth on said pin which is in line with and engages the guides in the plate G, substantially as shown and described. 95

In testimony whereof I have hereunto set my hand and seal in the presence of two subscribing witnesses.
